UNITED STATES PATENT OFFICE.

SAMUEL C. FISHER AND CHARLES C. FISHER, OF STEUBENVILLE, OHIO.

DRAW-BAR FOR RAILWAY-CARS.

SPECIFICATION forming part of Letters Patent No. 398,716, dated February 26, 1889.

Application filed September 22, 1888. Serial No. 286,058. (No model.)

To all whom it may concern:

Be it known that we, SAMUEL C. FISHER and CHARLES C. FISHER, both residents of Steubenville, in the county of Jefferson and 5 State of Ohio, have invented a certain new and useful Improvement in Draw-Bars; and we do hereby declare that the following is a full, clear, and exact description of the invention, which will enable others skilled in the 10 art to which it appertains to make and use the same.

This invention relates to an improvement in draw-bars.

The object is to produce a draw-bar which 15 shall be of such construction that should any of the parts become broken or injured from any cause they may be removed readily for the purpose of repair and without the necessity of entering the car. Furthermore, the 20 object is to produce a draw-bar which shall be simple of construction, efficient and durable in use, and comparatively inexpensive of production.

Heretofore it has been customary to secure 25 the draw-bar to the bottom of the car by means of bolts, which extend through the car-floor and into the interior of the car. Now, should any accident happen to the draw-bar, and should the car be loaded with any substance— 30 such, for instance, as grain—it will be necessary to unload the car in order to get at the bolts holding the draw-bar in place. It is the object to overcome these obstacles in a simple and effective manner; and to these ends 35 the invention consists in the improved construction and combination of the draw-bar, whereby the obstacles above mentioned will be overcome in a simple and effective manner.

In the accompanying drawings, forming 40 part of this specification, and in which like letters of reference indicate corresponding parts, we have illustrated one form of device embodying the essential features of our invention, although the same may be carried 45 into effect in other ways without in the least departing from the spirit thereof, and in these drawings—

Figure 1 is a bottom plan view showing the device secured to the frame of the car. Fig. 50 2 is a longitudinal vertical sectional view showing the manner in which the device is

secured to the car. Fig. 3 is a perspective view of the device, part of the frame-work of the car being cut away; and Fig. 4 is a detail view of one of the follower-plates.

Referring to the drawings, A designates the lower front portion of the bottom of a car, to which is secured the body-bolster 1 and the end sill, 2, having bumpers 3 mounted thereon. To the rear portion of the coupler-head 4 is 60 loosely secured a coupler-bar, 5, on which is mounted a washer, 6, the said coupler-bar extending back nearly to the body-bolster 1. Upon this coupler-bar 5 are mounted two follower-plates, 7 and 8, provided at each end 65 with openings 9 and 10, and in these openings are placed two rods, 11 and 12, which pass back and through the body-bolster and through a plate, 13, on the opposite side, and are held in place thereon by means of pins 14. 70 Upon the rods 11 and 12 are secured two buffers, 15, which are held together by means of bolts 16. In order to cause these buffers to be held at a certain distance apart, collars 17 are placed on the bolts, so that when the nuts 75 are tightened the collars will prevent the buffers from being drawn too close together.

Upon the rods 11 and 12 and between the follower-plates 7 and 8 are mounted two springs, 18, the ends of the rods extending 80 through the follower-plate 7, and are secured on their outer side by means of a pin, 19, which passes through an opening in the said rods. The coupler-bar 5 has also mounted upon it a spring, which bears at each end against the 85 follower-plates, the outer end of the said coupler-bar being provided with a collar, 20, held in place thereon by means of a pin, 21, which engages an opening, 22, in the said bar. The object of this spring on the coupler-bar 90 is to remove all strain from the same when the cars are being coupled or when being drawn over the track.

In order to strengthen the device additionally and to prevent the springs from bulging 95 up, and thus bearing against the rods upon which they are mounted, two L-shaped iron braces are placed on the bolt 16 between the edge of the collar and the side of the buffer and extend down and are secured by means 100 of bolts 23 to the beams 24 of the car.

Having now described the different parts

of our device, we will proceed to show its operation: Should the draw-bar become injured from any cause and it is desired to remove it, it will only be necessary to remove the pins 5 in the ends of the rods 11 and 12 and unscrew the bolts 24, holding the L-shaped iron braces in place, when the entire draw-head and coupler-bar may be removed.

It will thus be seen that, although this device is exceedingly simple of construction, it will be found highly efficient and durable in use, and will save a considerable loss of time and labor to railroad-men when it is necessary to remove the draw-bar.

Having thus fully described our invention, what we claim as new, and desire to secure by Letters Patent, is—

1. In a draw-bar, the combination of the coupler-head, a coupler-bar loosely secured thereto, apertured follower-plates on the coupler-bar, rods extending through the said plates, springs on the rods between the plates, buffers behind the plates, and bolts for holding the buffers in position, substantially as described.

2. In a draw-bar, the combination of the coupler-head, a coupler-bar loosely secured thereto, apertured follower-plates on the coupler-bar, rods extending through the said plates, springs on the rods between the plates, buffers behind the plates, bolts for holding the buffers in position, and L-shaped braces beneath the rods, substantially as and for the purpose specified.

3. The combination of the buffers, bolts for holding the same in place, and L-shaped braces secured to the said bolts, substantially as and for the purpose specified.

4. The combination, with a coupler-head, of a movable bar carrying a spring, substantially as described.

In testimony that we claim the foregoing as our own we have hereunto affixed our signatures in presence of two witnesses.

SAMUEL C. FISHER.
CHARLES C. FISHER.
